Primary Examiner — Melanie H Tung

(57) **CLAIM**

The ornamental design for a display screen with animated graphical user interface as shown and described.

DESCRIPTION

1.1 : First front view

1.2 : Second front view in changed state

1.3 : Third front view in changed state

1.4 : Fourth front view in changed state

1.5 : Fifth front view in changed state

1.6 : Sixth front view in changed state

1.7 : Seventh front view in changed state

1.8 : Eighth front view in changed state

The display screen with animated GUI shows a cursor indicating a position of the detected line of sight (a position viewed by the user) on a display of an information processing terminal (a digital camera, a smartphone, or the like) that detects the line of sight of the user for an operation input. The broken lines in reproduction Nos. **1.1-1.8** illustrate features that form no part of the claimed design. The appearance of the transitional image sequentially transitions between the images shown in reproduction Nos. **1.1-1.8**. The process or period in which one image transitions to another image forms no part of the claimed design. The tonal black and white grayscale in the reproductions is used to indicate a difference in contrast.

1 Claim, 8 Drawing Sheets
